JUG OR THE LIKE

Roy C. Josephsen, Hillsdale, Joseph R. Tino, Clifton, and Charles R. Fulcher, Bloomfield, N.J., assignors to W. R. Grace & Co., New York, N.Y., a corporation of Connecticut

Filed Aug. 18, 1964, Ser. No. 81,346

Term of patent 14 years

(Cl. D58—5)

FIG. 1.

FIG. 3.

FIG. 2.

FIG. 4.

The dominant features of our design reside in the portions shown in full lines.

We claim:

The ornamental design for a jug or the like, as shown and described.
